UNITED STATES PATENT OFFICE.

DAVID BROWN AND JOSEPH D. BRADLEY, OF NEW HAVEN, CONNECTICUT,
ASSIGNORS TO ROYAL O. DORMAN, OF SAME PLACE.

BUCKBOARD-WAGON.

SPECIFICATION forming part of Letters Patent No. 333,053, dated December 22, 1885.

Application filed June 11, 1885. Serial No. 168,427. (No model.)

To all whom it may concern:

Be it known that we, DAVID BROWN and JOSEPH D. BRADLEY, citizens of the United States, residing at New Haven, in the State of Connecticut, have invented new and useful Improvements in Buckboard-Wagons, of which the following is a specification.

Our invention relates to an improved buckboard-wagon, and has for its object to adapt the vehicle for short turning, and to provide increased elasticity of the wagon body or frame.

In the ordinary buckboard-wagon the reach is dispensed with, and the axles are connected by elastic parallel slats or strips of wood, forming a springing platform, on which the seat is mounted. The platform is but slightly elevated above the center of the wheels, and if made nearly as wide as the space between the wheels will prevent the wagon from being turned in a short space. If the platform is made narrow, its elasticity is reduced, and the wooden slats sag under the load imposed and remain deflected.

Our invention consists in the novel construction and arrangement of the slats forming the vehicle-body and in a novel auxiliary metal spring for strengthening the same, as hereinafter more particularly described and claimed.

In the accompanying drawings, Figure 1 is a side view of a buckboard-wagon embodying our improvements. Fig. 2 is a plan view of the under side of the body of the vehicle, and Figs. 3 and 4 show modifications of the slats forming the body or frame.

In the drawings, A designates the parallel wooden slats or strips which form the vehicle body or frame. The slats are arranged in two sets or series, and extend from the respective axles to about midway of the wagon. The rear slats are fastened at their rear ends to a transverse bed-piece or bolster, which is mounted on the back axle, b, and the forward slats are secured at their forward ends to a transverse bed-piece, which is mounted over and pivoted in the usual manner to the front axle, c. The slats curve upward from the axles, as shown, and are fastened at their opposite ends to parallel cross-bars d, which are connected by longitudinal bars e. The wagon-seat h is mounted upon the cross-bars d, and further strengthens the connection between the slats. Thus curved and connect-

ed the slats form a strong and graceful elastic frame, which is arched midway of its length, and has the wagon-seat surmounted directly over the arch or point of greatest elasticity.

Arranged under the vehicle-body is an auxiliary spring, L, which is shaped to conform to the arch in the frame. The spring is secured at its center to the middle stay, e, and is bent around under the slats A, following their curvature. The ends of the spring are fastened to transverse bars M, which are bolted across the horizontal part of the slats.

Constructed as above described and shown this form of buckboard-wagon can be turned in a very short space, as the forward wheels swing under the arch in the frame when the axle oscillates on its bolt or pivot. The arched frame also has greater strength and elasticity than the ordinary buckboard-wagon, and is more graceful in design.

When a two-seated wagon is desired, the rear ends, A', of the rear slats may project beyond the axle and curve upward like the forward ends, as shown in Fig. 3, forming a support for an additional seat.

If desired, the spring L may be dispensed with, and the arch properly strengthened by iron braces, stays, or leather cross-straps; but the spring insures superior elasticity, and is therefore preferable.

It is evident that the upper ends of the slats may be fastened to a single cross-bar or suitably secured to the bottom of the seat.

The body or frame of the wagon may also be made of a single series of slats, A'', bent upward near the middle to form an arch, as shown in Fig. 4.

We desire to secure by Letters Patent—

1. The combination of the front and rear series of slats A with the auxiliary spring L, having its ends attached to the respective series of slats, substantially in the manner and for the purpose specified.

2. In a double-seated buckboard-wagon having an arched frame, the rear series of slats, A', bent upward at each end to form an elastic support for the respective seats, substantially in the manner set forth.

DAVID BROWN.
